UNITED STATES PATENT OFFICE.

EDWARD DUMMER, OF AUBURNDALE, (NEWTON,) MASSACHUSETTS.

SUPPORT FOR SPINDLES AND RINGS OF RING-SPINNING MACHINES, &c.

SPECIFICATION forming part of Letters Patent No. 396,148, dated January 15, 1889.

Application filed August 3, 1887. Serial No. 246,075. (No model.)

To all whom it may concern:

Be it known that I, EDWARD DUMMER, a citizen of the United States, residing at Auburndale, in the city of Newton, county of 5 Middlesex, and State of Massachusetts, have invented a new and useful Improvement in Supports for Spindles and Rings of Ring Spinning and Twisting Machines, of which the following is a specification, reference being had to the accompanying drawings.

In ring-spinning frames the spindles are now commonly more or less flexibly supported, so that they, when carrying an unbalanced load, may gyrate, or so that any vibration 15 arising therefrom will not be communicated to the frame. A spindle thus supported may be of much less weight to carry the required load and may be run by means of less power than one for which there is no such provision, 20 since the spindle and load may revolve about their center of gravity, or nearly so; rather than about their geometrical center, when these centers do not coincide. Any force—such as results from the pull of the thread— 25 which tends to move the spindle out of such center of rotation necessitates greater weight in the spindle and more power to drive it than if such force did not exist.

While many different devices have been 30 employed whereby the spindle may have the lateral motion of gyration or vibration, the ring has heretofore been, so far as relates to lateral motion, rigidly fixed in the frame. In practice the thread, by which there is a 35 draft largely between and in like degree on the spindle and the ring, acts to pull the spindle out of its proper center of rotation. In all ring-spinning this pull is considerable, so that the bolster must be much more firmly 40 held than otherwise might be. For much ring-spinning and in all ring-twisters the bolster must be practically so rigidly held that the spindle cannot gyrate or vibrate, as desired. Furthermore, all gyratory or vibratory 45 motion of the spindle, owing to whatever cause, results, of course, in a constant or intermittent eccentricity of the spindle with reference to the fixed ring, which is very undesirable for many obvious reasons.

50 My invention has two main objects—first, to prevent that draft of the thread which is on both spindle and ring from pulling the

spindle out of its proper center of rotation, and, second, to maintain the spindle in the center of the ring, the general result being 55 that the spindle may have a much greater freedom in its gyratory or vibratory movement, and therefore will run much easier than heretofore, and also that the draft on the thread may be at all times the same, and the 60 thread will not be subjected to unequal strain or sudden jerks to an extent not before attained.

The invention consists in so combining the spindle with the ring for operation in the machine that the ring may have a lateral motion corresponding to that of the spindle, and that the pull by the thread on the ring may be caused to balance or counteract the pull on the spindle, as hereinafter set forth, and 70 specifically pointed out in the claims.

In the drawings, (two sheets,) Figure 1 shows an elevation, partly in section, of so much of a spindle, bolster, and support therefor, a ring, and means for connecting the ring with the 75 spindle and operating the ring as is sufficient to illustrate a device embodying my invention. Fig. 2 is a plan of the support or stand F. Fig. 3 is a plan of the bolster, arms b, and bearings c. Fig. 4 is a transverse central section of stand F. Fig. 5 is a transverse central section of the bolster, an arm, b, and a bearing, c. Figs. 6, 7, 8, 9, and 10 illustrate 80 modifications to adapt the invention to certain classes of spindle bearings and supports 85 or to differently-constructed machines.

The spindle A, whirl B, bobbin C, and ring D shown are each of a well-known form and construction. Referring, first, to Fig. 1 and illustrations of details thereof fixed to the 90 bolster a, which may also be like those in common use and located as required with reference to the whirl, are shown two arms, b, to each of which is fixed a bearing, c, in which may slide a rod, E, parallel or longitudinal with the spindle. To the upper ends of these rods is fastened the ring D. The stand or support F may be adjusted and fixed on the usual rail, G, in the common manner by means of the threaded stud d and nut e. 95 It has a vertical projection, f, thereon, with which the bolster a is pliably or flexibly connected. This may be effected by means of a packing, g, formed of any material known for 100

like purpose. This connection may be such that the bolster *a* and arms *b* may be suspended thereby, there being shoulders *a'* and *f'* on the exterior of the bolster and interior of projection *f*, as shown. The ring *D*, and hence rods *E*, are flexibly connected with a rail, *H*, which rail corresponds to the common ring-rail, and is to have a like vertical movement. This connection may be made by means of two spiral springs, *h*, each fastened at one end on a stud, *i*, on an arm, *i'*, applied or fastened to a rod, *E*, and at the other end on a stud, *j*, on an arm, *j'*, applied or fastened to the rail *H*. The step *k* for the spindle may be a removable piece set in the base of the stand or support *F*.

I have made such provision that the bearings for the spindle and also for the sliding rods *E* may be in a chamber for oil. Projecting downward from the stand or support *F* are two tubes, *l*, closed at the bottom, open at the top, and extending downward sufficiently to allow the rods *E* to enter therein the required distance. On the base of the stand or support *F* is secured a removable cap, *I*, as by means of screws *m*, there being some material, *n'*—such as leather—in a groove, *n*, in the base and between the base and cap. This cap has two tubular projections, *o*, to inclose the bearings *c*, and a tubular projection, *p*, to inclose the bolster *a*, these projections being of sufficient height to keep the bearings well oiled and of sufficient interior capacity to allow the lateral motion of the inclosed bearings.

The operation is simple. An unbalanced load on the spindle will cause the latter when revolved to gyrate. The bolster *a*, arms *b*, bearings *c*, rods *E*, and ring *D* will have a corresponding lateral motion, while the ring is moved up and down as required to build the thread on the bobbin, the rods sliding in their bearings *c*; hence the spindle, having been set with reference to the ring in the construction of the device so that their centers coincide, will always be in the center of the ring. The pull by the thread *u*, so far as it is alike in degree on the ring (by means of the usual traveler shown) and on the spindle, will have no effect on the gyratory motion, or to move the spindle out of its proper center of rotation, since the pull on the ring will, through the ring, bolster, and the connecting parts, act counter to the pull directly on the spindle.

It is true that the weight of the ring and parts connecting the same with the bolster add to the weight heretofore gyrated; but it is found that such additional weight is a restraint on the gyration in a far less degree than that heretofore required to overcome the pull of the thread and obtained by making the connection between the bolster and fixed support more or less rigid. In fact, while "top" or "balanced spindles"—common terms for spindles which may gyrate—are not practicable in twisting-frames in which the pull of the thread is great, and only to a cer-

tain extent in spinning-frames, my device not only may be employed on either, but the connection between the bearing of the spindle and the fixed support may be very flexible and allow an exceedingly free movement. So very flexible or yielding may such connection be that if the packing *g* is not desired it may be dispensed with, as hereinafter shown.

Fig. 6 shows a modified construction in which the step for the spindle is fixed to or within the piece forming the bolster, which is typical of a certain class of spindle-supports. The bearings for the rods *E* are connected with the bolster by means of a tube, *q*, which is fixed to the bolster at the upper end. Thus the spindle may run in oil, while the bearings for the rods *E* are not surrounded by oil. It is not so necessary that the bearings for the rods be in oil, since their slow movement causes but little friction compared with that of the rapidly-revolving spindle.

Fig. 7 shows how my invention may be adapted to another class of spindle-supports, by means of which the spindle may vibrate, or, perhaps more properly, by means of which the vibration caused by the spindle when carrying an unbalanced load is prevented from being communicated to the supporting-rail. Elastic or flexible material, *J*, is placed between the support and the rail. With such construction I fix the arms *b* directly to such support, so that the ring vibrates with the spindle. Thus the centers of the spindle and ring will always coincide and the pull of the thread will react on the spindle, as above set forth.

The leading distinctive feature of my invention is the interposition of a connecting medium between a ring and the yielding or flexibly-supported bolster of the appropriate spindle, so that when the bolster has a lateral motion bolster and ring will move laterally as one; and, since this my invention is a radical departure from what has heretofore been known, I do not wish to have it limited by details of construction in such a manner as to lose the spirit thereof.

The invention is applicable to any of the devices providing for gyration or vibration of the spindle. There may be many modifications which might occur to those skilled in manufacturing or operating spindles. There may be only one arm *b* and rod *E*. (Illustrated by dispensing with one arm *b* and rod *E* of Fig. 1.) The lower ends of rods *E* may be connected with a vertically-moving rail, *H'*, below the rail *G*, as illustrated by Figs. 9 and 10, instead of to a rail, *H*, located above the rail *G*, as in Fig. 1. This may be the construction when the rods are not inclosed by the oil-receptacles, as in Fig. 1. Other means than the springs *h* of Fig. 1 may be employed for flexibly connecting the sliding rods with the rail, as links *h*² (illustrated by Fig. 9) or pliant wires *h*³, as in Fig. 10. The bolster may extend downward as one piece or a rod and have the arms or medium connecting with the

ring slide thereon, as illustrated by Fig. 8, in which the moving rail H' is below the spindle-rail, and the arms b' , to which the rods E' are fixed, are adapted to slide on a rod, r , joined to the bolster. With such construction the spring h' or flexible connection with the movable rail may be central, as shown. This flexible connection with the moving rail may serve to maintain the spindle in a vertical position, or one approximately so, and to such extent that in many cases the packing g between the bolster and the fixed stand or support may be dispensed with, the bolster having a shoulder, s , or the like, and the stand or support a shoulder or socket, t , as shown in Fig. 8.

Considerable convenience and economy arises from the fact that the device may be manufactured and made ready for transportation and use as a complete article comprising both the ring and spindle support, which article may be readily and easily applied to the frame when set up in the factory where it is to be operated, certain work and care which has heretofore been required to fit and adjust the ring on the frame, and the spindle-support with reference to the ring, being dispensed with.

I claim as my invention—

30 1. The combination, with a spindle, a spindle-bolster, and means for supporting said bolster in a yielding or flexible manner, of a ring, and connections between said bolster and ring, whereby the ring is caused to gyrate or vibrate with the bolster and spindle, substantially as specified.

2. The combination, with a spindle, a spindle-bolster, and means for supporting said bolster in a yielding or flexible manner, of a ring, and sliding connections between said bolster and ring, whereby the ring is caused to gyrate or vibrate with the bolster and spindle, substantially as set forth.

3. The combination of a fixed support, a spindle, a spindle-bolster, means for connecting said bolster with said fixed support in a yielding or flexible manner, a ring, sliding connections between said bolster and ring, and a rail movable in the direction of the length of the spindle and connected flexibly with said ring, substantially as set forth. 45

4. The combination, with a spindle, a spindle-bolster, means for supporting said bolster in a yielding or flexible manner, a ring, and sliding connections between said bolster and ring, whereby the ring is caused to gyrate or vibrate with the bolster, of a support or stand containing a chamber for oil inclosing the bolster and the bearings of said sliding connections, substantially as set forth. 55

5. The combination, with a spindle, a spindle-bolster, means for supporting said bolster in a yielding or flexible manner, a ring, and connections between said bolster and ring, whereby the ring is caused to vibrate or gyrate with the bolster, of a support or stand containing an oil-chamber inclosing the bolster, substantially as set forth. 65

6. The combination of a spindle, a yieldingly or flexibly supported spindle-bolster, rods adapted to move longitudinally and in the direction of the length of the spindle, bearings for said rods fixed to the spindle-bolster, and a ring fixed to said rods, substantially as set forth. 70

7. The combination of a spindle, a bolster therefor flexibly supported, rods adapted to move longitudinally and in the direction of the length of the spindle, bearings for said rods fixed to the spindle-bolster, a ring fixed to said rods, and receptacles for oil into which said rods extend, substantially as specified. 80

EDWARD DUMMER.
